UNITED STATES PATENT OFFICE.

JOSEPH BERCHA, OF BEATRICE, NEBRASKA.

COMB-CLEANING DEVICE.

1,040,849.

Specification of Letters Patent.

Patented Oct. 8, 1912.

Application filed February 14, 1911. Serial No. 608,545.

To all whom it may concern:

Be it known that I, JOSEPH BERCHA, a citizen of the United States, residing at Beatrice, in the county of Gage and State 5 of Nebraska, have invented new and useful Improvements in Comb-Cleaning Devices, of which the following is a specification.

This invention relates to comb cleaners and more particularly to that type of device 10 which is adapted to effectively clean the teeth of hair combs.

One of the main objects of the invention is the provision of a device of this character having a plurality of taut wires which are 15 mounted upon the frame and crossed in its center so as to form converging cleaning elements which grip the sides of the teeth and when the comb is removed the dirt is scraped off the teeth.

20 A further object of the invention is the provision of a simple, cheaply constructed and efficient frame for supporting crossed wires and carrying an adjusting head by which the tension of the wires may be regulated.

25 Further objects of the invention will appear as the following specific description is read in connection with the accompanying drawing, which forms a part of this application, and in which:—

Figure 1 is a perspective view. Fig. 2 is a longitudinal section. Fig. 3 is an enlarged diagrammatic perspective showing the arrangement of the wires. Fig. 4 is an enlarged detail perspective view of a portion of one of the wires.

Referring more particularly to the drawings, 1 represents a frame which comprises a single piece of heavy iron or steel wire 40 having its separate legs 2 and 3 arranged in parallel relation and upturned at one end, as at 4, to provide head plate attaching legs 5. The opposite ends of the legs are connected together by the converging members 45 6 which are arranged at right angles to the legs 2 and 3 and which terminate in an eye 7, for a purpose to be hereinafter described. Mounted upon the legs 5 and rigidly held in engagement therewith by means of a 50 flange 8 is a head plate 9 centrally apertured, as at 10, to receive the handle attaching screw 11 by which the handle 12 is connected to the frame.

Slidably mounted upon the legs 2 and 3 adjacent the opposite end from the head 9 55 is a sliding head 13 which is right angular in outline and has an aperture 14 formed in its vertical portion which is adapted to permit the passage of an adjusting screw 15 which also is extended through the eye 7 60 and is provided, on its outer end, with a thumb nut 16.

Each of the heads 9 and 13 is provided on its upper edge with a series of outwardly inclined teeth or projections 17 over which is 65 looped the cleaning wire 18. This cleaning wire is preferably composed of a plurality of twisted strands and in looping the wire from one head to the other it is crossed, as shown at 19, so as to provide constricted 70 passages 20, so that when the teeth of the comb to be cleaned are pressed into engagement with the wire near one end and are drawn toward the opposite end into the constricted passages, the wires will grip the 75 teeth of the comb and, when the comb is drawn out at right angles to the wires, the wires will effectively strip all dirt therefrom. The comb may be then removed and started in at the opposite end and forced to- 80 ward the end of initial starting when the opposite side of the teeth will be cleaned.

Having thus described the invention, what I claim as new is:—

A device of the class described comprising a pair of parallel legs having upturned ends, a stationary head secured to said ends, the opposite ends of the legs being connected together, a loop in said connection, a second head slidably mounted on said legs, 85 outwardly extending projections on said heads, a flexible wire looped back and forth between the projections, a bolt carried by the movable head and passed through the loop, a knurled adjusting nut on the bolt 90 bearing against the loop, and a handle rigidly secured to the stationary head.

In testimony whereof I affix my signature in presence of two witnesses.

JOSEPH BERCHA.
